[57] CLAIM

The ornamental design for a pair of battery connector posts, as shown and described.

DESCRIPTION

FIG. 1 is a perspective view of the negative member of the pair of battery connector posts showing my new design;

FIG. 2 is an elevation view taken at 2—2 of FIG. 4;

FIG. 3 is a top plan view of the battery connector post of FIG. 1;

FIG. 4 is a front elevation view thereof;

FIG. 5 is a bottom cutaway view taken at 5—5 of FIG. 4;

FIG. 6 is a perspective view of the positive member of the pair of battery connector posts showing my new design;

FIG. 7 is an elevation view taken at 7—7 of FIG. 9;

FIG. 8 is a top plan view of the battery connector post of FIG. 6;

FIG. 9 is a front elevation view of the battery connector post of FIG. 6;

FIG. 10 is a bottom cutaway view taken at 10—10 of FIG. 9; and,

FIG. 11 is a perspective view of a pair of battery connector posts showing my new design.
